UNITED STATES PATENT OFFICE.

JOE TORTOMASI, OF SAN DIEGO, CALIFORNIA.

LIFE-SAVING FLOAT.

1,234,826.

Specification of Letters Patent. Patented July 31, 1917.

Application filed January 3, 1917. Serial No. 140,363.

To all whom it may concern:

Be it known that I, JOE TORTOMASI, a subject of the King of Italy, residing at San Diego, in the county of San Diego and State of California, have invented certain new and useful Improvements in Life-Saving Floats, of which the following is a specification.

This invention relates to new and useful improvements in life saving floats.

10 The primary object of the invention is the provision of a float serviceable in time of shipwreck for the safe deposit of goods and as a ready means for maintaining persons afloat upon the water.

15 A further object of the device is the provision of an article-receiving float comprising separable portions adapted for provision upon shipboard for use in rescuing passengers in case of accidents to the ship.

20 With these general objects in view, and others that will appear as the nature of the invention is better understood, the same consists of the novel construction, combination and arrangement of parts hereinafter more 25 specifically described and pointed out in the appended claims.

In the drawings, forming a part of this application and in which like-designating characters refer to corresponding parts 30 throughout the several views,

Figure 1 is a side elevation of the device,

Fig. 2 is a central, diametrical sectional view thereof,

Fig. 3 is a top plan view of the same partially broken away,

Fig. 4 is an enlarged elevational view of a side portion of the device, illustrating the retaining means, and

40 Figs. 5 and 6 are enlarged detailed sectional views, taken adjacent one of the locking members.

Referring more in detail to the drawings the device broadly consists of two hollow hemispheres 10 and 11, suitably formed of 45 metal secured together in spherical formation by means of a plurality of locking latches 12.

Each of the said hemispheres 10 and 11 has a circular head 13 at one side thereof, 50 the heads of the hemispheres being adapted to flatly engage each other, as best shown in Fig. 2 of the drawing. Complementally arranged annular ribs 14 and receiving sockets 15 therefor are provided on the said 55 heads for co-operating and preventing relative side movements of the two hemispheres

when operatively arranged in engagement with each other.

The latches 12 are pivoted as at 16 within recesses 17 of the hemisphere 10, said recesses being adapted to aline with similarly formed sockets 18 in the hemisphere 11. Spaced lugs 19 are arranged in the sockets 18, between which bolt extensions 21 of the latches 12 are adapted to seat, being retained in position by lock nuts 22, and a plurality of these locking devices being employed, the two hemispheres are readily maintained in spherical form thereby.

The spherical float is adapted to support 70 persons, preventing them from drowning, and a plurality of links 23 are swingingly mounted upon each of the hemispheres for ready seizure by persons desiring to use the float, the arms of such persons being readily 75 thrust through the links 23, if desired. By releasing the latches 12 the hemispheres 10 and 11 may be separately employed for floating purposes.

A threaded closure member or plug 24 80 is provided for a port 25 that is arranged through the pole of each of the hemispheres. Any desired articles may be readily inserted within the device to be safely retained therein while floating which articles may 85 be thereafter removed when the float is picked up.

A side pocket or compartment 26 is provided in the hemisphere 11, formed by means of a partition wall 27 within the said 90 hemisphere, the wall of the latter having an opening 38 therein normally closed by a hinged door 39 and maintained closed by a lock 40. Water-tight packings 41 are provided for the door 39, whereby the articles 95 positioned within the compartment 26 for safe keeping will be kept both dry and safe until removed when the float or the hemisphere 11 is rescued.

A serviceable float is arranged adapted 100 for saving both persons and articles, the device being of simple construction and easily operated.

What I claim as new is:—

1. A device of the class described comprising two hollow metallic hemispherical floats, means for connecting the floats including latch connections between the said floats, hand links carried by the latter, receiving ports at the poles of said hemispheres, screw 105 threaded closure plugs provided for the said ports, a partition within one of said hemi-

spheres, providing a compartment therein, and a water-tight door portion provided for the said compartment.

2. A device of the class described comprising two hollow hemispheres, one of the latter having its head arranged with annular receiving grooves, annular ribs arranged upon the head of the other hemisphere positioned within the said grooves when the heads are in flat engagement with each other with the hemispheres in their spherical arrangement, the adjacent portions of said hemispheres having sockets

and recesses therein adapted for alinement with each other, spaced lugs in each of said sockets, latches pivoted in said recesses and having a swinging movement within the said sockets, bolt extension upon said latches adapted for seating between the said lugs when the latches are positioned within said sockets and lock nuts carried by the said bolts in adjustable engagement with the said lugs.

In testimony whereof I affix my signature.

JOE TORTOMASI.

Copies of this patent may be obtained for five cents each, by addressing the "Commissioner of Patents, Washington, D. C."
